UNITED STATES PATENT OFFICE.

JOHN D. BURTON, OF PITTSBURG, PENNSYLVANIA.

METAL ROOFING.

SPECIFICATION forming part of Letters Patent No. 406,024, dated July 2, 1889.

Application filed February 5, 1889. Serial No. 298,781. (No model.)

To all whom it may concern:

Be it known that I, JOHN D. BURTON, of 5
Pittsburg, in the county of Allegheny and
State of Pennsylvania, have invented a new
and useful Improvement in Metal Roofing;
and I do hereby declare the following to be a
full, clear, and exact description thereof.

My invention relates to an improvement in
sheet-metal roofing; and it consists in cutting
10 sheets of metal into form and turning the edges
and joining them together, as will hereinafter
more fully appear, and as represented in the
drawings.

To enable others skilled in the art to make
15 and use my invention, I will describe its con-
struction.

In the accompanying drawings, which form
part of my specification, Figure 1 represents
the roof of a building when the sheets and
20 comb-piece are in position. Fig. 2 shows the
manner of securing the sheets together.

In the drawings, A represents the form or
shape of the sheets of metal, the upper portion
of the sheets having the edges B turned
25 over outwardly and the lower portion turned
under or inwardly, the sheets being provided
with nail-holes D.

In placing the sheets on the roof the lower
edges of the first row of sheets—viz., those
30 next the eaves of the building—are flat-
tened out or turned down and secured to

the timbers. The upper or outward-turned
edges B then hook into the lower or inner-
turned edges C (shown in dotted lines in Fig.
2) of the next course of sheets, and so on until
35 the comb-piece is reached, when the angle-
shaped piece E is placed in position over the
upper edges of the top course of sheets. The
sheets are held to the sheeting by driving
nails into openings D.

When the sheets and comb-piece are in po-
sition, the roof will present a neat appearance
and be perfectly water-tight.

Having thus described my improvement,
what I claim is—

A metal roofing consisting of sheets of metal
having their upper edges turned over upon
themselves, forming a parallel fold and meet-
ing in a point, and their lower edges turned
under upon themselves, forming a parallel
50 fold and meeting in a point, having the squared
corners and the cut-out portions in the metal
of the upper turned-over edge to allow the en-
trance of the fastening devices, substantially
as described.

In testimony whereof I have hereunto set
my hand this 26th day of April, A. D. 1888.

J. D. BURTON.
